UNITED STATES PATENT OFFICE

151,571

DESIGN FOR A DUMMY PLUG FOR ELECTRIC OUTLETS

George H. Tillinghast, Burlington, N. J.

Application July 31, 1946, Serial No. 132,149

Term of patent 14 years

(Cl. D26—1)

To all whom it may concern:

Be it known that I, George H. Tillinghast, a citizen of the United States, residing at Burlington, in the county of Burlington and State of New Jersey, have invented a new, original, and ornamental Design for Dummy Plugs for Electric Outlets, of which the following is a specification, reference being had to the accompanying drawing, forming part thereof.

Fig. 1 is a front elevation of a dummy plug for electric outlets, showing my new design.

Fig. 2 is a perspective view of the front of the plug.

Fig. 3 is a plan view of the same.

Fig. 4 is a perspective view showing the plug as viewed from the rear.

I claim:

The ornamental design for a dummy plug for electric outlets, as shown.

GEORGE H. TILLINGHAST.
